Primary Examiner — Barbara Fox*Assistant Examiner* — Lilyana Bekic(74) *Attorney, Agent, or Firm* — Dorsey & Whitney LLP(57) **CLAIM**

We claim the ornamental design for a reservoir for oral irrigator, as shown and described.

DESCRIPTION

FIG. 1 is a front isometric view of a reservoir for oral irrigator showing our new design;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the reservoir for oral irrigator that form no part of the claimed design.
